UNITED STATES PATENT OFFICE

2,415,298

SLIDE BUTTON SWITCH

William C. Linton, Washington, D. C., assignor
to Fuse Indicator Corporation, Rockville, Md.,
a corporation of Delaware

Application October 10, 1944, Serial No. 558,057

4 Claims. (Cl. 200—167)

1

The present invention relates to wall switches for use in conventional electrical light, heat and power circuits which visibly designate the open condition of the electrical circuit, whereby one may more readily locate the switch when the latter is installed in dark or secluded places, having among its principal objects the provision of a sliding push-button switch whereby the circuit closer thereof may be manually opened and closed and which button completely houses the means of connection between the switch box and the cover plate therefor, in order that the general exterior appearance of the switch will be greatly improved over the type of wall switches now in vogue.

Other objects will be in part obvious and in part pointed out in the following accompanying description, which will set forth what I believe to be novel and my invention.

In the drawings:

Fig. 1 is a plan view of the switch embodying the present invention.

Fig. 2 is a side elevation of the same.

Fig. 3 is an end elevation of the same.

Fig. 4 is a longitudinal vertical section through the switch.

Fig. 5 is a vertical transverse section through the switch.

Fig. 6 is a detail horizontal section taken on the line 6—6 of Fig. 5 in the direction of the arrow points.

Fig. 7 is an enlarged plan view of a blank from which the supporting bar is formed.

Fig. 8 is an enlarged vertical longitudinal section through a slightly modified form of the switch with the lens for the lamp and cover plate removed.

Fig. 9 is a vertical transverse section of the switch with the cover plate removed.

Fig. 10 is a plan view of the switch casing as shown in Fig. 8 with one section thereof removed.

Fig. 11 is a similar view of the entire casing.

Fig. 12 is an enlarged end view of the removable section of the casing.

Fig. 13 is an end view of the same taken from the opposite end of that shown in Fig. 12.

Fig. 14 is a side elevation of the same.

Fig. 15 is a vertical longitudinal section taken on line 15—15 of Fig. 16 in the direction of the arrow points.

Fig. 16 is a plan view of the same.

Fig. 17 is a vertical longitudinal section through the lens.

Fig. 18 is a bottom plan view of the same.

2

Fig. 19 is a vertical transverse section through the same on a slightly enlarged scale.

Fig. 20 is an enlarged end elevation of the sliding block, and

5 Fig. 21 is a plan view of the same.

Referring now more particularly to the accompanying drawings wherein like and corresponding parts are designated by similar reference characters throughout the several views, I 10 have herein shown a supporting bar 1 which is first stamped or cut from a piece of sheet metal, as shown in Fig. 7 of the drawings, and finally formed in the shape as shown in the remaining figures of the drawings. This supporting bar 15 has an enlarged medial portion 2 in which is formed a rectangular opening 3 and projecting within this opening 3 are a pair of ears 4, each having a threaded opening 5 formed therein. Also formed within the enlarged portion of the

20 supporting bar are the threaded openings 6, and slots 7 are formed in the opposite ends of the bar through which may extend screws, bolts or other fastening means which are employed for attaching the supporting bar to the standard cutout 25 box, whereby the switch may be suspended within the cutout box and the wires of the electrical circuit extending within the cutout box connected thereto. The opposite edges of the enlarged portion 2 of the supporting bar are bent downwardly

30 to form the depending flanges 8.

The cover plate 9 has a rectangular opening formed therein which is of the same size as the opening 3 formed within the supporting bar and these openings register with one another. The 35 cover plate also has formed therewith a pair of apertured projections 10 through which extend the attaching screws 11 and the lower ends of these screws are engaged within the threaded openings 5 of the supporting bar, whereby, the 40 cover plate may be rigidly connected and supported thereupon.

The switch casing 12 has a pair of apertured projections 13 formed with an extending from the opposite ends thereof through which extend 45 the screws 14 and these screws are in threaded engagement with the openings 6 formed within the supporting bar, whereby, the switch casing may be attached to and suspended from the supporting bar 1.

50 Supported within this casing 12 by means of the two conductors 15 is a liquid contact circuit closer or button 16 of a design as is illustrated and described in Patent No. 2,101,092, issued December 7, 1937. Each contact member 15 is provided with 55 a terminal screw 17 to which are connected the

conductors of the electrical circuit, whereby, when the circuit closer 16 is moved to the position as is illustrated in Fig. 4 of the drawings, the electrical circuit will be closed but when this button 16 is moved in an anticlockwise direction, the electrical circuit in which it is included will be opened.

Attached to and adapted to oscillate with the circuit closer 16 is a sectional bracket 18 having a recess 19 formed therein. In order to transmit an oscillatory movement to the circuit closer 16, I provide a sliding block 20 having depending from its lower end a lug 21 which fits within the recess 19 of the bracket, whereby, when said block 20 is moved in opposite directions, the circuit closer 16 will be oscillated for opening and closing the electrical circuit to which it is connected.

The casing 12 is provided with a removable U-shaped section 22 having an apertured ear 23 formed with one end thereof which is adapted to register with one of the projections 13 formed with the casing, whereby, when a set screw 14 is inserted therethrough, the removable section 22 will be fastened to the main portion of the casing as well as the supporting bar 1. The inner faces of the parallel arms of the removable section 22 are each provided with a slot 24 in which travel the lower flanges 25 of the sliding block 20. Depending from each of the parallel arms of the section 22 are the flanges 26 which normally extend down within the casing and rest upon the upper faces of the conductors 15 for retaining the latter in place, as well as preventing the upward movement of the circuit closer 16. Projecting from the opposite faces of these parallel arms of the section 22 are the flanges 27, which latter extend upwardly within the rectangular opening 3 formed within the supporting bar 1 and adapted to ride upon the upper faces of these flanges 27 are the flanges 28 formed with the sliding block 20. In assembling the switch, the sliding block 20 may be first inserted through the opening 3 formed within the supporting bar and the removable section 22 of the casing first inserted in place, whereby, the flanges 25 of the supporting bar will be moved into position within the slots 24 of this removable section of the casing, whereby, the sliding block 20 will be locked within the supporting bar 1 and yet permitted to slide within the opening 3. The main portion of the casing 12 having the circuit closer 16 arranged therein is moved to a position whereat it will receive the removable section 22 of the casing and the two sections of the casing are then connected to the supporting bar 1 by means of the screws 14.

The sliding block 20 has formed in its upper face a depression 29 in which is seated a lamp 30 of the gaseous type. One lead wire 31 of the lamp extends downwardly through an opening 32 formed within the block 20 and is connected to one of the terminals 17, whereas, the other lead wire 33 of the lamp is connected to a leak resistor 34 seated within a recess formed within the upper face of the sliding block 20. A conductor 35 is connected at one end to the other terminal 17 or that terminal opposite to which the lead wire 31 is connected and the opposite end of this conductor 35 extends upwardly through an opening 36 and is also connected to the leak resistor 34. The recess 37 formed within the upper face of the block 20 is divided into two sections by means of a partition 38 but is entirely filled with a leak resistor 34 consisting of a plastic composition as is illustrated in Fig. 4. By means of this partition 38, the lead wires 31 and 33 are separated from one another but connected by means

of the leak resistor 34. From this arrangement, it will be obvious that the lamp 30 and leak resistor 34 are connected in series with the terminals 17 but in parallel to the circuit closer 16, whereby, when the circuit is opened, the current will be permitted to flow to the lamp 30 for causing the same to glow but when the circuit is closed by means of the circuit closer 16, the current will pass through the latter and cause the lamp to be extinguished.

The lamp is housed upon the block 20 by means of a lens 39, which latter is preferably molded from a transparent or translucent material, whereby, the rays of light from the lamp 30 may emit therefrom. The inner side walls of the lens 39 are provided with recesses 40 which receive the projections 41 formed with the block 20 and a detachable snap connection is effected between the lens 39 and the projections 41 whereby when pressure is manually applied to the lens 39 in the directions of the arrows, as shown in Fig. 4 of the drawings, the lens, together with the block 20, will be caused to slide in opposite directions for oscillating the circuit closer 16. The opposite ends 25 of the block 20 are provided with the recesses 42 which receive the projecting ends of the lugs 4 formed with the supporting bar 1 and the lugs 10 formed with the cover plate 9, in order that the sliding block may have the advantage of moving the entire length of the openings formed within the supporting bar and cover plate.

Whereas, in the foregoing I have illustrated a conventional mercury switch, in Figs. 8 to 11 of the drawings, I have illustrated a mechanical snap switch which may be substituted for the mercury switch. In mounting the snap switch within the casing, I have formed within the casing a pair of standards 43 having recesses 44 formed in their upper ends for receiving and providing bearings for the opposite ends of a U-shaped circuit closer 46. When the circuit closer 46 is moved to the position as shown in Fig. 8 of the drawings, the electrical circuit to which it is included will be opened but when oscillated in an opposite direction, the lower ends of this circuit closer 46 will engage the spring contacts 47 for closing the electrical circuit. These spring contacts 47 are connected to the conductor bars 48 and the latter have terminal screws 49 with which may be connected the conductors of the wiring system in which the switch is included. Arranged between the circuit closer 46 and the lug 21 of the block 20 is a coil spring 50 and seated upon the upper end of this coil spring 50 is a recessed cap 51, which is at all times in contact with the lug 21, whereby, when the block 20 is moved, the coil spring will first be compressed for exerting a pressure upon the circuit closer 46 and when the lug 21 is to one side of a vertical center line in which the ends of the circuit closer are journaled, the latter will be caused to move in a direction opposite to that to which the lug 21 has been moved, in order that the circuit closer 46 may be moved into and out of engagement with the spring contacts 47. In order to limit the movement of the circuit closers 16 or 46, stops 52 are formed with and projecting inwardly within the casing 12.

From the foregoing, it is obvious that any conventional type of circuit closer may be employed and mounted within the casing 12, and when the circuit closer is moved to its open position, the lamp 30 will glow but when the circuit closer is moved to its closed position, no current will be

permitted to flow to the lamp and, therefore, the latter will be extinguished.

From the foregoing, it is also quite obvious that only a single push-button is required for manually opening and closing the circuit breaker and that the lens forming part of this push-button at all times covers the screws 24 so as to hide the same from view. When the cover plate is installed within a wall of a building, no fastening means are visible and the cover plate, as well as the lens 39 of the push-button, may be of any desired color or combination of colors or may be further ornamented to greatly increase the external appearance of the switch and its cover plate over those of the conventional switches and cover plates therefor now in vogue.

Manifestly, the construction herein shown is capable of considerable modification and such modifications as come within the scope of my claims, I consider within the spirit of my invention.

I claim:

1. An electric wall switch comprising in combination a casing having a switch mechanism arranged therein, a removable cover plate extending over the switch mechanism within said casing, screws for connecting said cover plate to said casing and being removable from the outer face of said plate, a switch button longitudinally movable within and extending through said cover plate, covering means extending completely over said screws and means for connecting said covering means to said switch button whereby the same may be moved longitudinally over said cover plate without uncovering said screws.

2. An electric wall switch comprising in combination a casing having a switch mechanism arranged therein, a removable cover plate extending over the switch mechanism within said casing, screws for connecting said cover plate to said casing and being removable from the outer face of said plate, a switch button longitudinally removable within and extending through said cover plate, said screws each being positioned within said cover plate at points beyond that through which said switch button extends, a lens extending over and covering each screw, and means for detachably connecting said lens to said switch button whereby said cover plate may be

removed from the casing without removing said switch button.

3. An electric wall switch comprising in combination a casing having a switch mechanism arranged therein, a removable cover plate extending over said casing for housing the switch mechanism therein, screws for connecting said cover plate to said casing and being removable from the outer face of said cover plate, a switch button slidably supported within said casing and extending through said cover plate, said screws being arranged within said cover plate at points beyond that through which said push button extends, a lamp indicator arranged with said push button, a lens for completely covering said lamp indicator and screws and means for connecting said lens to said switch button whereby the same may be moved longitudinally over said cover plate without uncovering said screws.

4. An electric switch comprising in combination a supporting bar, a sectional casing consisting of a main section and a removable section, said main section having a recess therein for receiving said removable section, a switch mechanism arranged within said casing, flanges formed with and extending from said removable section for retaining said switch mechanism within said casing, an operating knob, means for slidably mounting and supporting said knob within said removable section of the casing, means for connecting the sections of said casing to said supporting bar whereby said knob will be retained in operative connection with said switch mechanism, a cover plate removably connected to said supporting bar and said operating knob extending through and slidably mounted in said cover plate.
